(57) **CLAIM**

The ornamental design for a protective cover for laptop, as shown and described.

DESCRIPTION

FIG. 1 is a first perspective view of a protective cover for laptop showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of another state of the protective cover for laptop thereof;

FIG. 10 is an enlarged view of the selected portion in FIG. 2;

FIG. 11 is an enlarged view of the selected portion in FIG. 2; and,

FIG. 12 is an enlarged view of the selected portion in FIG. 4.

The broken lines shown in the drawings depict portions of the protective cover for laptop in which the design is embodied that form no part of the claimed design.

1 Claim, 12 Drawing Sheets(56)
